UNITED STATES PATENT OFFICE.

IVAN C. BUSHONG, OF OTTAWA, KANSAS.

STEEL POLE AND METHOD OF MAKING THE SAME.

Application filed March 24, 1924. Serial No. 701,393.

The present invention relates to steel pole or mast constructions, and aims to provide an improved pole or mast of tapered form and same general design as that employed for the carrying of electric cables in electric power transmission systems.

One special object of the improvements is to devise a steel pole or mast unit which is adapted to be constructed from I-beam or H material, by cutting the web of the I-beam and reassembling the same to provide a steel pole or mast unit having the same character of cross-section, but producing a pole or mast possessing a uniform taper throughout its length.

For this purpose, I have devised a new method or process of construction, whereby I-beams may be so cut and reassembled as to produce a steel pole or mast of the nature described. In carrying out this novel method, I cut through the web of the I-beam, lengthwise, and along a diagonal line from end to end of the beam, reverse the sections end for end and reunite the severed edges of the web portion of the beam, to produce a permanent connection and resulting in a pole or mast of the desired tapered form.

It is also sought to provide a novel pole or mast construction in which the same is not limited to a single web portion, but may be produced by a plurality of I-beams cut diagonally and reassembled in the manner above referred to, but with their web portions in intersecting relation.

With the foregoing general objects in view, the invention will now be described by reference to the accompanying drawing, illustrating both the improved pole construction and process of making the same, after which the novel features therein will be particularly set forth and claimed.

In the drawing—

Figure 1 is a plan view illustrating a steel pole or mast constructed in accordance with the present invention;

Figure 2 is a similar view illustrating the character of I-beam employed in constructing the new pole or mast;

Figure 3 is a section taken on the line III—III of Figure 2;

Figure 4 is a plan view illustrating the two separated portions of an I-beam when cut as indicated by the dotted line in Figure 2.

Figure 5 is an enlarged transverse section, taken on the line V—V of Figure 1;

Figure 6 is a similar sectional view, but showing the I-beam after it has been cut on an incline for producing beveled edges along the line of cut;

Figure 7 is a similar sectional view of the I-beam, as cut in Figure 6, and thereafter reassembled with the severed portions in reversed relation; and

Figure 8 is a sectional view illustrating a steel pole or mast construction made up of a pair of I-beams in the fashion shown in Figures 1 and 5, but with their web portions united in intersecting relation.

Referring now to the drawing in detail Figures 2 and 3 illustrate the character of I-beam which is used for constructing the tapered form of steel pole or mast forming the subject of the invention. The first step in the method of producing this new mast construction is the cutting of the web portion 10 of the I-beam along a diagonal line, as indicated at 11, whereby two duplicate tapered I-beam sections 10' are produced, as illustrated in Figure 4. The next step of the process is simply the reversal of these I-beam sections 10', end for end, bringing the cut edges 11 again into abutting relation, as illustrated in Figures 1 and 5, after which the edges 11 of the sections 10' are permanently soldered or welded together by any suitable and practical means well known for this purpose.

This method or process obviously produces a practical and efficient form of steel pole or mast unit, which is of the desired tapered form or outline, and possesses all the requisite strength and rigidity for its use as a pole or tower structure, due to the I-beam form of cross section as shown in Figure 5. The method of producing this type of unit is of an extremely simple and economical nature, and adapted to be carried out in a practical manner in shops designed generally for this class of work.

After the welding of the sections 10' in their final form as illustrated in Figure 1, the resulting pole or mast section may be suitably punched, as illustrated at 12, to produce a series of steps designed for use in the usual manner for enabling the workmen to ascend to the top of the tower.

In Figures 6 and 7 is illustrated a modified form of construction, due to the use of a slightly different method of producing the cut for severing the I-beam. In this modified method, a slightly inclined shearing cut

11' is made, producing the beveled edges along the severed web portions 10', as illustrated in Figure 7, where the sections of the beam are shown as reassembled in reversed relation, end for end. Obviously, in this reassembling of the I-beam sections, with the edges 11' in abutting relation, a V-shaped space 14 is produced between the beveled edges 11', along the line of cut, which is desirable in some instances as affording a more ample space for the application of the welding material, as will be readily understood.

In Figure 8, I illustrate a construction which makes use of a plurality of the I-beam, which are cut and finally reassembled in the manner above explained, with the exception that after the first unit has been reassembled with the cut portions of the beam in reversed relation, as shown in Figures 1 and 5, the second beam is arranged in the same manner but on opposite sides of the reconstructed first beam, and permanently connected thereto in this manner, with the final result that the severed parts of both beams have their web portions united along substantially a common line, and with all parts of both beams tapering in the same direction. This obviously produces a steel pole or mast unit having multiple projections or lobe portions extending out from a common center, and thus affording a correspondingly higher degree of strength, rigidity and firmness of construction.

It is thus apparent that I have provided a highly efficient and practical form of pole or mast construction for tower work, which constitutes a material advance or improve-

ment over the type of construction generally used by virtue of the practically continuous web portion of the structure in lieu of the more or less open work which characterizes the prevailing type of tower unit.

Having described the invention, what I claim to be new and desire to secure by Letters Patent, is:

1. A steel pole or mast of intersecting I-beam cross-section and having web portions of substantially continuous and uniformly tapered form from one end of the pole to the other and intersecting with each other along the middle longitudinal lines thereof.

2. The method of constructing a tapered steel pole or mast from an I-beam, which consists in cutting the I-beam lengthwise by a diagonal cut through its web portion, and at an angle to the plane of said web portion, reassembling the severed parts in endwise reversed relation, whereby a V-shaped groove is provided along the edges produced by the cutting action, and securing said parts together by the application of welding material along said groove.

3. The method of constructing a tapered steel pole or mast from I-beams, which consists in cutting said beams lengthwise by diagonal cuts through their web portions, and reassembling the severed parts of the beams and uniting the web portions along a common line with all said parts tapering in the same direction.

In witness whereof I hereunto affix my signature.

IVAN C. BUSHONG.
